UNITED STATES PATENT OFFICE.

JOHN F. MEEKER, OF STAMPS, ARKANSAS.

FLUE-EXPANDER.

1,024,802.

Specification of Letters Patent. Patented Apr. 30, 1912.

Application filed October 14, 1911. Serial No. 654,608.

To all whom it may concern:

Be it known that I, JOHN F. MEEKER, a citizen of the United States, residing at Stamps, in the county of Lafayette and 5 State of Arkansas, have invented certain new and useful Improvements in Flue-Expanders, of which the following is a specification, reference being had to the accompanying drawings.

10 This invention comprehends certain new and useful improvements in tube or flue expanders, and the invention has for its primary object a simple, durable and efficient construction of device, whereby all tendency 15 of the tool to stick in the flue will be avoided, the invention consisting in certain constructions and arrangements of the parts that I shall hereinafter more fully describe and claim.

20 For a full understanding of the invention, reference is to be had to the following description and accompanying drawing in which,

Figure 1 is a side elevation of my improved flue expander partly broken away 25 and in section. Fig. 2 is an inner face view of one of the sections of the device. Fig. 3 is an end view of the body portion of the tool. Fig. 4 is a detail perspective view of 30 one of the rollers employed, and, Fig. 5 is a detail view of the tapering mandrel.

Corresponding and like parts are referred to in the following description and designated in the accompanying drawings by like reference characters.

35 My improved flue expanding tool embodies a sectional body portion 1, the same, in the present instance, embodying three corresponding tapered sectoral sections formed with rounding extremities 2 and 3, each section being formed with a concave inner face, with a convex outer face and with transversely extending exterior grooves near each 40 end, said grooves being annular when the sections are assembled and being designated,

45 respectively, 4 and 5, and adapted to receive contractile spring bands designated 4' and 5', respectively. Each section is further formed with a longitudinal radially disposed and outwardly tapering opening 50 tending therethrough, the openings being designated 8 and extending into an intermediate shoulder formed on each section, the side walls of said openings 8 at the edge of the respective shoulders being somewhat

contracted, as indicated at 10. The openings 8 are designed to accommodate preferably cylindrical rollers 11 which are adapted to protrude outwardly from the openings 8 into engagement with the flue and which are held in place as against 55 outward displacement by means of the contracted portions 10 formed on the side walls of said openings. The body portion 1 is formed at one end with a centrally disposed bore 7 communicating at one end with 60 the openings 8, the body portion being formed at its opposite end with a central bore 9, constituting a continuation of the bore 7.

12 designates the mandrel which is 70 formed with a tapering stem or shank 13 and with a polygonal or many sided end 14 to which a wrench or other tool may be applied so as to turn the mandrel.

From the foregoing description in connection with the accompanying drawings, the operation of my improved flue expanding tool will be apparent. In the practical use of the device, the mandrel is inserted through the bores 7 and 9 in between the 80 rollers 11 and the tool is inserted in the flue to be expanded. Should one of the rollers 11 strike an obstruction in the flue, it will stop, but the next roller comes up behind it and forces the first one over the obstruction 85 and smooths the latter out without the necessity of removing the mandrel or of stopping the tool, all liability of binding being prevented, owing to the fact that the body portion is sectional and that the mandrel not 90 only serves to expand the rollers by direct contact therewith, but also serves to expand the sections of the body portion, when operating in flues of sizes larger than the one in which the tool will fit in its relatively 95 contracted condition.

Having thus described the invention, what I claim is:—

A flue expanding tool, including a body portion, comprising tapered sectoral sections, each having a concave inner face and a convex outer face, the sections being formed near their ends with transversely extending grooves, and intermediate of said grooves with a shouldered portion and with 100 longitudinally extending outwardly facing openings intersecting the shouldered portion, contractile springs encircling the 105

grooves of the sections, rollers held in the longitudinally disposed openings of the respective sections with peripheries in open relation to each other, and a tapering mandrel 5 insertible through the sectional body portion in direct engagement with the rollers, as for the purpose set forth.

In testimony whereof I hereunto affix my signature in the presence of two witnesses.

JOHN F. MEEKER.

Witnesses:

T. M. PRIBBLE,

ARCH A. HALLIBURTON.
